UNITED STATES PATENT OFFICE.

WILLIAM J. KEELEY, OF NEW YORK, N. Y., ASSIGNOR TO AUTO PNEUMATIC ACTION COMPANY, A CORPORATION OF NEW YORK.

AUTOMATIC GRAND PIANO.

1,168,645.

Specification of Letters Patent.

Patented Jan. 18, 1916.

Application filed October 11, 1911. Serial No. 654,104.

To all whom it may concern:

Be it known that I, WILLIAM J. KEELEY, a citizen of the United States, residing at New York, in the county of New York and State of New York, have invented a new and useful Automatic Grand Piano, of which the following is a specification.

The object of this invention is to improve the arrangements and constructions used in automatic grand pianos and the invention particularly relates to an improved arrangement for the operating pedals and motor.

The invention is shown in the accompanying three sheets of drawings in which—

Figure 1 is a front elevation of parts of an automatic grand piano with my improvement applied thereto. Fig. 2 is an enlarged view of the depending casing. Fig. 3 is a sectional elevation thereof showing the pedals in operative position. Fig. 4 is a similar view illustrating the pedals in inoperative position, and Fig. 5 is a view similar to Fig. 3 on a somewhat smaller scale illustrating a modification.

Referring to the drawings and in detail, A—A designates the frame of a grand piano, B the key board, C the key bed, and D the keys of a grand piano. Depending from the structure and under the key bed is a casing E preferably made rectangular in cross section. This casing is provided at its front with an opening 10.

11 designates a door or panel. The door or panel is provided with four bearing blocks 12 which fit into grooves or slots cut in the casing so that the same can be slid upwardly to uncover said opening or downwardly to cover said opening. A bell crank lever 13 is pivoted inside of the casing and the long arm thereof connects by a link 14 to a block 15 secured near the bottom of the door or panel at substantially the center thereof. The short end of the bell crank lever is connected by a link 16 to an arm 17 which is mounted on a shaft 18 journaled in blocks secured to the bottom of the key bed C and which shaft has an operating handle or lever 19 secured on its outer end.

A spring 20 is secured between a block 21 secured on the bell crank lever and a screw 22 inside of the casing. The spring is arranged so as to exert its heaviest pull as the handle 19 is swung as indicated in dotted

lines in Fig. 1 to raise the door and also is arranged so as to hold the door in its open position as shown in Fig. 2, the spring thus substantially counter-balancing the weight of the door.

23—23 designates a pair of pedals which are pivoted to a bar or block 24. This bar 24 has arms 25—25 extending therefrom, the ends of which are bent downwardly and outwardly and are pivoted in blocks 26—26 secured inside of the casing E. Each pedal 23 connects by a link 27, bell crank lever 28, and link 29 to the movable member 30 of a feeder or bellows F. These feeders F—F are mounted or carried on a suitable wind-trunk G secured to the bottom of the piano structure. The bell crank levers 28 are pivoted on brackets 31 secured on the sides of the casing E, as shown.

By this arrangement the door can be opened and the pedals swung to operative position, as shown in Fig. 3, or the pedals can be swung into inoperative position up inside of the casing and the door closed, as shown in Fig. 4. A block or bar 32 is carried across the casing and the pneumatic operating motor M for the music sheet manipulating mechanism is mounted on said bar. This motor may be of any ordinary or approved construction and connected to the wind trunk G by the passage G' (Fig. 3). The shaft of the motor M is connected to operate the note sheet manipulating mechanism N by means of the usual sprocket wheels and sprocket chains. By housing the parts in the manner described a very ornamental and compact arrangement is provided which does not detract from the appearance of the ordinary grand piano.

The pedals P—P'—P² which are employed when the piano is played manually may be pivoted to the casing, as indicated in Fig. 1.

In Fig. 5 a modification is shown in which each bracket 31 which supports the bell crank lever 28 is secured to the bottom of the casing. In this arrangement an extra link 33 is arranged between each link 27 and bell crank 28 and a swinging link 34 is arranged to support the links at the point of their connection. In this modification the motor M is arranged above the line at which the pedals are swung up into the casing, while in the preferred form of the invention

shown in the other figures of the drawings, the motor can be arranged above and also slightly at the rear of the position the pedals occupy when they are swung up into the casing, as illustrated in Fig. 4.

The details and arrangements herein shown and described may be greatly varied by a skilled mechanic without departing from the scope of my invention as expressed 10 in the claims.

Having thus fully described my invention, what I claim and desire to secure by Letters-Patent is:—

1. An automatic grand piano having, in 15 combination, a depending casing positioned under the central portion of the key board and of substantially less depth from front to back than either width or height, said casing containing a pneumatic note-sheet- 20 operating motor and having an opening in the front side of said casing, a door slideable into and out of position to close said opening, pneumatic feeders disposed horizontally closely adjacent the under side of the 25 piano bed and extending forwardly into the upper part of said casing, and a pair of pedals operatively connected to the feeders and mounted to be swung upward into said casing, said casing also comprising means

for supporting said motor within the casing 30 and beneath said feeders.

2. An automatic grand piano having, in combination, a depending casing positioned under the central portion of the key board and of substantially less depth from front 35 to back than either width or height, said casing containing a pneumatic note-sheet-operating motor and having an opening in the front side of said casing, a door slideable into and out of position to close said opening, pneumatic feeders disposed horizontally 40 closely adjacent the under side of the piano bed and extending forwardly into the upper part of said casing, and a pair of pedals operatively connected to the feeders by substantially vertical links and mounted to be 45 swung upward into said casing, said casing also comprising means for supporting said motor within the casing, beneath said feeders and above the position occupied by the 50 pedals when in inoperative position.

In testimony whereof I have hereunto set my hand, in the presence of two subscribing witnesses.

WILLIAM J. KEELEY.
